DRUM OR PULLEY ATTACHMENT

Filed July 13, 1926

Patented June 7, 1927.

1,631,899

UNITED STATES PATENT OFFICE.

STEFAN A. TALJAN, OF EAST ST. LOUIS, ILLINOIS.

DRUM OR PULLEY ATTACHMENT.

Application filed July 13, 1926. Serial No. 122,249.

This invention relates to drum or pulley attachments for the wheels of vehicles to enable the use of the vehicle as a hoisting or power device or to enable the vehicle to apply its own power, so that it may be disengaged from a mud-hole.

An important object of the invention is to provide a device of this character which may be readily applied to a vehicle and removed therefrom and which is capable of application to vehicles, the wheels and hubs of which are of different sizes.

A further object of the invention is to provide a device of this character which may be readily and cheaply produced, which will be durable and efficient in service and a general improvement in the art.

These and other objects I attain by the construction shown in the accompanying drawings, wherein for the purpose of illustration is shown a preferred embodiment of my invention and wherein:

Figure 1 is an inner face view partially in section of a drum constructed in accordance with my invention;

Figure 2 is a vertical sectional view showing the drum applied to a vehicle wheel;

Figure 3 is a section on the line 3-3 of Figure 2;

Figure 4 is a plan view of one of the spoke engaging elements;

Figure 5 is an illustration of the cable for use with the drum.

Referring now more particularly to the drawings, the numeral 10 designates the spokes of a vehicle wheel and 11 the outer plate of the pair usually employed for maintaining the inner ends of the spokes in assembled relation. On automobile wheels, this outer plate is extended outwardly to provide the hub 12 of the wheel. The opening 15 of the drum 14 receives the hub 12.

In accordance with my invention, I provide the inner face of the drum 14 with a plurality, preferably three, of chordally directed guides 16, the inner faces of which are slotted, as at 17, to permit passage of the stems 18 of the slides 19 operating within the guides. The ends of the guides 16 are preferably provided with stops preventing escape of the guides therefrom. The slide stems 18 are preferably circular in cross section and provided with heads 20. Upon the stems are slidably mounted yokes 21, the outer ends of which are hinged at 22 to one arm of U-shaped spoke clamps 23, the oppo-

site arm of which spoke clamp has pivoted thereto a keeper 24, the free end of which has an opening 25 for the passage of a threaded stud 26 projecting from the yoke 21. At the opposite or outer side of the drum, I secure a plurality of radially directed tubes 27, the outer end of each of which is closed, as at 28, with the exception of an axially disposed opening 29. Through this opening 29 is directed a shaft 30 having suitable collars 31 which prevent longitudinal movement thereof. The outer end of the shaft is provided with a thumbscrew 32 whereby it may be rotated and at the inner end thereof is threaded for engagement in the threaded bore 33 of a jaw carrier 34. This carrier has at its outer end a jaw 35, the inner face of which is toothed for engagement with the hub portion 12. In applying the device to the vehicle wheel, the drum is slipped over the hub and pushed toward the spokes of the wheel as far as possible. The spoke clamps are then attached to the spokes of the wheel and the keepers 24 thereof secured in position. It is pointed out that in applying the spoke clamps to the spokes, the slidable mounting of these spoke clamps will permit adjustment to compensate for any slight misalignment of the spoke, while the rotatable mounting of the clamp and the hinged connections thereof permit the clamp to be readily secured about the spoke. The yoke 21 being of less length than the stem 18 will permit adjustment of the clamps toward and away from the drum, so that proper engagement with the spoke may be had. When the spoke clamps are all applied, the jaws 35 are shifted into engagement with the hub 12 by rotating the thumbscrews 32 until the jaws are sufficiently firmly engaged with the hub to insure against rotation of the drum.

It will be obvious that a device of this character may be very readily attached to the vehicle and is capable of application to wheels which vary considerably in construction.

In the use of the drum 14, it may be employed either as a hoisting device or as a drive for machinery by jacking up the wheel to which the drum is applied. By securing to the drum one end of a cable, such as shown in Figure 5, the opposite end of which is secured to some fixed object, the drum may be employed for withdrawing

a vehicle from a mudhole or the like. The cable illustrated in Figure 5 is provided at one end with a hook 36 engageable in an opening 37 formed in one of the end walls 5 of the drum 14. The opposite end of this cable has attached thereto hooks 38 and 39 for engagement with a peg or post providing an anchor. It will be obvious that with the device attached in this manner, the cable 10 will be wound upon the drum, moving the vehicle toward the peg or post and thus withdrawn from a mudhole in which it has settled.

Since the construction hereinbefore set 15 forth is obviously capable of a certain range of change and modification without materially departing from the spirit of the invention, I do not limit myself to such specific structure except as hereinafter claimed.

20 I claim:—

1. A drum for attachment to the hubs of spoked wheels having an opening for the passage of the hub, circumferentially spaced slides shiftable chordally of the drum at the inner face thereof, spoke engaging clamps carried by said slides and means at the outer face of the drum and shiftable radially thereof for clampingly engaging the hub of the wheel.

2. A drum for attachment to the hubs of spoked wheels having an opening for the passage of the hub, circumferentially spaced slides shiftable chordally of the drum at the inner face thereof, spoke engaging clamps carried by and shiftable longitudinally upon said slides and means at the outer face of the drum and shiftable radially thereof for clampingly engaging the hub of the wheel.

3. A drum for attachment to the hubs of spoked wheels having an opening for the passage of the hub, circumferentially spaced slides shiftable chordally of the drum at the inner face thereof, spoke engaging clamps carried by and rotatably mounted upon said slides and means at the outer face of the drum and shiftable radi-

ally thereof for clampingly engaging the hub of the wheel.

4. A drum for attachment to the hubs of 50 spoked wheels having an opening for the passage of the hub, circumferentially spaced slides shiftable chordally of the drum at the inner face thereof, spoke engaging clamps carried by and rotatably and longitudinally shiftable upon said slides and means at the outer face of the drum and shiftable radially thereof for clampingly engaging the hub of the wheel.

5. A drum for attachment to the hubs 60 of spoked wheels having an opening for the passage of the hub, circumferentially spaced slides shiftable chordally of the drum at the inner face thereof, spoke engaging clamps carried by said slides, means 65 at the outer face of the drum and shiftable radially thereof for clampingly engaging the hub of the wheel, the clips being substantially U-shaped, there being a yoke surrounding the guide to which one arm of the 70 clip is hinged and a catch hinged to the other arm of the guide and adapted for connection with the yoke.

6. A drum for attachment to the hubs of 75 spoked wheels having an opening for the passage of the hub, circumferentially spaced slides shiftable chordally of the drum at the inner face thereof, spoke engaging clamps carried by said slides, means at the outer face of the drum and shiftable radially 80 thereof for clampingly engaging the hub of the wheel including tubes secured to the drum and extending radially thereof, a threaded member directed into the tube from the outer end thereof and held against longitudinal movement toward the outer end 85 of the tube and a threaded tube in which the threaded member is engaged having at its inner end a jaw for engagement with the hub of the wheel.

In testimony whereof I hereunto affix my signature.

STEFAN A. TALJAN.
